GOLF BALL CLEANER HAVING A TANK WITH SCRUBBING MEANS THEREIN

Joseph S. Garske, St. Paul, Minn., assignor to Par Aide Products Co., St. Paul, Minn., a corporation of Minnesota

Application January 18, 1955, Serial No. 482,466

15 Claims. (Cl. 15—21)

This invention relates to a ball cleaner and more specifically relates to a vertically reciprocable golf ball cleaning device which immerses and scrubs all portions of the ball.

An object of my invention is to provide an improved ball cleaning device of relatively simple and inexpensive construction and operation which scrubs all portions of the ball surface, including the indents therein, by moving the ball in a unique and improved manner against scrubbing means.

Another object of my invention is the provision of a ball cleaning device of the class described wherein the golf ball is revolved about its own center against surface scrubbing means and in addition is moved in a spiralling orbital motion against the scrubbing means for cleansing the ball and for rotating the same and thereby causing all portions of the ball surface to engage the scrubbing means.

Still another object of my invention is to provide a ball cleaning device of the class described which, when not in use, is substantially sealed to restrict entrance of rain water and foreign material and to restrict evaporation of the ball-cleaning fluid therein and which will thereby be easily maintained for efficient operation.

A further object of my invention is the provision of a golf ball cleaner of the class described which at all times confines a ball placed therein so that the ball will not pop out or be impelled out in an uncontrolled manner and which is constructed so that the ball must be lifted out.

These and other objects and advantages of my invention will more fully appear from the following description made in connection with the accompanying drawings wherein like reference characters refer to the same or similar parts throughout the several views and in which:

Fig. 1 is a sectional elevation view taken longitudinally through the device substantially at 1—1 as indicated in Fig. 2.

Fig. 2 is a transverse section view of the device taken on a line substantially at 2—2 of Fig. 1 and being partly in top elevation;

Fig. 3 is a section view of the device taken substantially at 3—3 of Fig. 1;

Fig. 4 is a section view taken substantially at 4—4 of Fig. 1;

Fig. 5 is a section view taken substantially at 5—5 of Fig. 1;

Fig. 6 is a detail top plan view of one of the brushes constituting the scrubbing means of the device;

Fig. 7 is a front elevation detail view of the backing of the brush shown in Fig. 6 but having the bristles removed for sake of clarity;

Fig. 8 is a transverse sectional view of an alternative form of the ball cleaning device and being a similar view to Fig. 3 but at a reduced scale with respect thereto; and

Fig. 9 is a view similar to Fig. 7 of the brush backing

2

utilized in the alternative form of the invention shown in Fig. 8.

The ball cleaning device which is designated in general by numeral 15 is provided with a housing or tank 16. Tank 16 is provided with an upstanding substantially circular side wall 17 to which is secured a cover plate 18 and to which is also secured, and in the form shown, has integrally thereof, an elongated cylindrical guiding member 19, the interior of which communicates with the interior of tank 16. A removable plug 19a is threadedly secured in the lower end portion of the sleeve 19. An upstanding and substantially annular support wall 20 is formed integrally of tank 16 and is disposed inwardly of the outer wall 17 to define a liquid storage chamber 21 therebetween. Wall 20 is provided with a number of apertures 22 which provide liquid communication therethrough. Wall 20 is also provided with a pair of inwardly extending lips 23 or abutments which, in the form shown, extend partially around wall 20 in diametrically opposed relation to each other. A ledge 24 is formed in the tank wall inwardly of and adjacent to the bottom portion of the inner wall 20 and has a groove or channel 25 formed therein.

Cover 18 is removably affixed to the side wall 17 of tank 16 by any suitable means such as screws 26. Cover 18 is provided with an enlarged opening disposed centrally thereof and at the peripheral edge of said opening is provided with an annular seat 27. A pair of inwardly opening recesses or channels 28 are cut in the annular seat 27 and top 18 to provide guide or camming bearings.

An elongated and rigid ball-carrying element designated in general by numeral 29 is mounted in tank 16 in a generally upright position and constitutes a paddle or plunger. Paddle 29 is of generally rectangular cross section and is twisted about an axis extending longitudinally therethrough so as to dispose the lateral side portions thereof helically about said axis. The lateral side portions of paddle 29 extend into the channels 28 of cover 18 to be guided thereby. The marginal portion of the paddle provides a camming surface which engages the bearings of top 18 provided by channels 28.

Cover or closure member 30 is affixed to or formed integrally of paddle 29 at its upper end portion and is of substantially annular shape so as to substantially sealingly engage the annular seat 27 of top 18. A handle 31 is rotatably mounted on paddle 29 in alignment with said axis extending longitudinally therethrough.

Paddle 29 is vertically shiftable in tank 16 and through the top 18 thereof and in the direction of the longitudinal rotation axis thereof and is provided with means for guiding the same in vertical shifting movement. Such means include an elongated shaft 32 which is affixed to paddle 29 and extends downwardly therefrom into the tubular portion 19 of tank 16. A bearing 33 is affixed to shaft 32 and is slidably and rotatably engaged with the interior of the tubular sleeve portion 19 of tank 16. Shaft 32 is twisted about the longitudinal axis thereof which is aligned with the axis of paddle 29 so as to helically dispose the lateral side portions thereof and to provide camming surfaces for rotating the shaft and paddle. A cam bearing 34 is affixed to tank 16 as by set screws 34a and slidably engages the twisted or helically disposed camming surfaces of shaft 32. A stop member 35 is affixed to shaft 32 and is vertically shiftable therewith into engagement with bearing 34 which provides an abutment for restricting the upward movement of paddle 29 and shaft 32.

Paddle 29 is provided with an enlarged oblong opening 36 therein adjacent the lower end portion thereof which is disposed diagonally or obliquely of the rotation axis of paddle 29 and of the direction of vertical move-

ment thereof. Opening 36 is of substantially larger size than the diameter of a golf ball and is adapted to receive and carry such a ball therein. The end portions of the obliquely disposed oblong opening 36 are of such size that such a golf ball may lodge therein so as to be disposed eccentrically of the axis of rotation of paddle 29.

Yieldable scrubbing means are provided in tank 16 and in the form shown, such scrubbing means comprise a pair of elongated, arcuately curved and helically shaped brushes 37 and 38, one of which is shown in detail in Figs. 6 and 7. The rigid backing members of the brushes are mounted against the upper lip portion 23 of inner wall 20 and in the grooves 25 adjacent to the lower portion of inner wall 20. The backings of brushes 37 and 38 are retained against the lip 23 by a flange or abutment 39 of cover 18. The bristles of brushes 37 and 38 provide radially inwardly extending protuberances which, at their inner end portions, define a central opening of slightly less diameter than the diameter of the golf ball and are thereby adapted to engage the same. Each of the brushes 37 and 38 extend less than half way around the inner wall 20 and are spaced apart from each other to define between the opposed lateral side portions thereof a pair of elongated and generally upright channels or passageways 40 which are helically shaped and which receive and carry the lateral side portions of paddle 29 therethrough. A portion of the bristles of each of the brushes 37 and 38 may engage paddle 29 and thereby assist in the guiding thereof in rotation as the same is shifted vertically. Each of the brushes 37 and 38 has a rib 37a and 38a respectively affixed to the outer surface thereof and extending slightly outwardly therefrom. A pair of cooperating ribs 26a are formed in opposite sides of the inner wall 20 and extend radially inwardly therefrom to define a groove for receiving rib 37a and 38a therein. The brushes are thereby precluded from shifting laterally or peripherally of inner wall 20.

Of course such scrubbing means could be constructed of a relatively firm and resiliently yieldable material such as rubber having radially extending protuberances defining the central opening for the ball.

In the alternative form of the invention shown in Figs. 8 and 9, the helically shaped brushes are substantially identical to the brushes shown in the first mentioned form of the invention and they are of substantially identical shape except that they are formed in short segments 50a, 50b and 50c, as shown in Fig. 9. In this form of the invention, there will be no inwardly extending lip corresponding to lip 23 of inner wall 20 as shown in Fig. 1 but there will be provided channels or flanges 51 affixed to the inner tank wall 52 for slidably receiving and securing the brushing segments in the tank.

Paddle 29 may be constructed of any suitable rigid material such as a metal, but in the preferred form the paddle is constructed of a rigid plastic material.

The portion of top 18 which extends upwardly from annular seat 27 thereof provides a retainer for precluding the golf ball from rolling off the top thereof when the ball supporting seat formed in opening 36 of paddle 29 is elevated to the top of the device.

In operation a liquid cleaning agent such as water having a quantity of detergent therein will be inserted into the tank and the liquid may circulate through the tank and through apertures 22 thereof. The handle 31 will be manually gripped and will be shifted upwardly to pull the paddle 29 out of the tank so as to shift opening 36 above the top 18. The ball will be inserted into opening 36 as indicated by the dotted line and the handle will thereafter be shifted downwardly. The bearings in cover 18 formed by channel 28 will engage the helically disposed side portions of paddle 29 and the bearing 34 will engage the helically twisted shaft 32 and the paddle side portions will engage the scrubbing means to thereby cause the paddle to revolve about the axis extending longitudinally

therethrough as the paddle is shifted downwardly into the tank and upwardly through the top thereof. As the paddle is shifted downwardly into the tank, the paddle is revolved and the ball will engage the scrubbing means and will thereupon shift into the upper portion of the obliquely disposed oblong opening 36 and be eccentrically disposed and revolved about the rotation axis of paddle 29. Action of the brushes against the ball will cause the same to be turned about its own center in several directions to cause all of the surface area of the ball to be engaged and scrubbed by the bristles. Because the ball is eccentrically disposed relative to the paddle rotation axis while being shifted downward, substantially more pressure exerted by the ball against certain portions of the brush than against the other portions of the brush so as to cause the ball to be rotated in several directions as it is moved downwardly through a spirally orbital path. The ball will be urged against the brushes with sufficient force so that the bristles thereof will efficiently clean the ball surface and the indents therein. When the paddle is again raised, the paddle will revolve, and the ball will be lodged eccentrically of the paddle rotation axis in the lower end of the obliquely disposed oblong opening 36, and the ball will follow a spiral orbital path and be turned about its own center in multi-directions and scrubbed by the brushes. After the paddle has been vertically reciprocated several times, the ball will be clean and may be removed by uplifting the handle and paddle so as to cause the stop element 35 to engage the bearing 34 and to position the ball seat defined by opening 36 substantially at the level of annular seat 27 of top 18. Even if the handle is violently lifted upwardly the ball will not pop out because it will be retained from vertical movement by the upper portion of the paddle and will be restricted in movement transversely of the vertical travel thereof by the retainer adjacent seat 27 of top 18.

When the ball has been cleaned and removed from the cleaning device the paddle will thereafter be shifted downwardly into the tank and cover 30, which is affixed to the paddle, will substantially sealingly engage the annular seat 27 of cover 18 and will thereby restrict entrance of rain water or foreign material into the tank. The liquid in the tank will thereby be maintained at its full strength and will not be dirtied or contaminated by natural causes.

It will be seen that I have provided an improved ball cleaning device which may be inexpensively manufactured and maintained which scrubs all portions of a golf ball by whirling the same eccentrically around an axis and against scrubbing means which turns the ball on its own center and thereby engages and cleans all of the surface thereof including the indents therein.

It should also be apparent that I have provided a golf ball cleaning device which not only confines the ball therein so that the ball will not pop out or be compelled out in an uncontrolled manner, but will also substantially seal out rain and foreign material when the ball cleaning device is not in use.

It will, of course, be understood that various changes may be made in the form, detail, arrangement and proportion of the parts without departing from the scope of my invention which consists of the matter described herein and set forth in the appended claims.

What is claimed is:

1. A ball cleaning device comprising a substantially enclosed housing having an opening in the top thereof and being adapted to contain a quantity of liquid, an elongated plunger of generally oblong cross section and of thickness substantially less than the diameter of such a ball, said plunger being twisted about an axis extending longitudinally therethrough, and said plunger having an enlarged opening therethrough for receiving and carrying such a ball therein, and said plunger being shiftably mounted in a generally upright position in said housing for vertical movement, said housing having guide bear-

ing means slidably engaging said plunger and constructed and arranged for rotating said plunger about said axis when the same is shifted vertically, and scrubbing means mounted in said housing adjacent said plunger and engaging the ball carried thereby, and said plunger having an upstanding handle mounted thereon for rotation about said axis, whereby said plunger will carry a ball in the opening thereof and be revolved when vertically reciprocated to expose surface areas of the ball adjacent to each other and progressively therearound to the scrubbing means for engagement therewith and scrubbing thereby.

2. A ball cleaning device comprising a substantially enclosed tank for containing a quantity of liquid therein and having an open upper portion, an elongated paddle having lateral side portions and also having an enlarged opening extending therethrough for receiving and carrying such a ball therein, said paddle being shiftably mounted in an upright position for longitudinal movement into and out of said tank through said open upper portion thereof, said paddle being twisted about an axis extending longitudinally therethrough for disposing said paddle side portions helically about said axis, yieldable scrubbing means mounted in said tank and protruding substantially radially inwardly thereof toward the opening in said paddle for engaging and cleaning such a ball therein, said scrubbing means having a pair of elongated and helically shaped channels formed therein and disposed in circumferentially spaced relation with each other and opening inwardly to receive and slidably carry the lateral side portions of the paddle therein and thereby rotate the paddle when the same is vertically shifted, and a handle coaxially and rotatably mounted on said twisted paddle and extending outwardly of the open upper portion of said tank, whereby when a ball is carried in the opening of said paddle and the paddle is vertically reciprocated to cause rotation thereof, the ball will be engaged and progressively cleaned therearound by the scrubbing means.

3. The structure recited in claim 2 and including a cover connected with said paddle and shiftably therewith into substantially sealing engagement with the upper portion of the tank when said paddle is shifted downwardly therein.

4. The structure recited in claim 2 and including a pair of paddle-guiding bearings mounted on the tank and in the open upper portion thereof, said bearings engaging said twisted paddle and rotating the same when the paddle is vertically shifted.

5. A ball cleaning device comprising a substantially enclosed tank for containing a quantity of liquid therein and having an open upper portion, an elongated paddle having lateral side portions and being twisted about an axis extending longitudinally therethrough for disposing said lateral side portions spirally about said axis, said paddle having an enlarged oblong opening therethrough extending generally obliquely of said axis and said opening having enlarged ball-receiving end portions which are respectively disposed on opposite sides of said axis and above and below each other and which are constructed and arranged to receive and carry such a ball eccentrically of said axis, and said paddle being shiftably mounted in an upright position in said tank for vertical reciprocating movement through the upper portion thereof, yieldable scrubbing means mounted in said tank and protruding inwardly toward said axis for engaging such a ball and defining a central opening similar in size to the diameter of such a ball, said scrubbing means having elongated and helical passageways therein extending generally upwardly and downwardly and opening inwardly to receive the spirally disposed lateral side portions of the paddle therein, an elongated shaft extending coaxially of said paddle and having a spiralling cam surface thereon of substantially the same pitch as that of the spirally disposed paddle lateral side portions, a cam bearing slidably engaging said spiralling cam surface of said shaft and producing relative rotation of said shaft and said

bearing when the same are slidably moved relative to each other in a direction longitudinally of said shaft, said cam bearing and said elongated shaft being connected with said tank and said paddle, one being affixed to said tank and the other being affixed to said paddle and rotating said paddle about said axis when the same is vertically reciprocated, whereby when such a ball is placed in said obliquely disposed oblong opening and said paddle is thereafter vertically reciprocated and rotated, said ball will shift in said oblong opening to one end portion thereof when the paddle is moved downwardly to be eccentrically moved about said axis by said paddle and into engagement with said scrubbing means which cleans and independently revolves the ball, and when said paddle is shifted upwardly the ball will shift to the opposite end portion of said oblong opening and into eccentricity with said axis to again be cleaned and revolved by said scrubbing means.

6. A ball cleaning device comprising a substantially enclosed tank for containing a quantity of liquid therein and having an open upper portion, an elongated paddle having lateral side portions and also having upper and lower end portions, said paddle having an enlarged opening extending therethrough adjacent said lower end portion being adapted for receiving such a ball therein, said paddle being shiftably mounted in an upright position for longitudinal movement into and out of said tank through the open upper portion thereof, and said paddle being twisted about an axis extending longitudinally therethrough for disposing said lateral side portions thereof helically about said axis, yieldable scrubbing means mounted in said tank and protruding inwardly thereof toward said axis, said scrubbing means comprising a pair of arcuate and elongated scrubbing elements helically shaped about said axis and extending substantially parallel to said paddle, and said scrubbing elements being spaced apart for receiving said paddle therebetween, said paddle having a helically disposed camming surface, a cam bearing affixed to said tank and engaging said camming surface for rotating said paddle as the same is vertically reciprocated, and a handle coaxially and rotatably mounted on said twisted paddle and extending outwardly through the open upper portion of said tank, whereby when said paddle is vertically shifted to rotate in said tank, said ball will engage said scrubbing elements to be independently rotated and cleaned thereby.

7. The structure recited in claim 6 and wherein said scrubbing elements have a plurality of protuberances extending substantially radially inwardly toward said axis and having inner end portions which cooperate to define an elongated substantially cylindrical opening about said axis of slightly less diameter than the diameter of such a ball, whereby substantially all portions of the ball may be engaged and efficiently cleaned by said scrubbing means.

8. The structure recited in claim 6 wherein said scrubbing elements are constructed of relatively firm rubber having radially inwardly extending protuberances for engaging, cleaning and rotating such a ball.

9. The structure recited in claim 6 wherein said scrubbing elements comprise helically shaped brushes having rigid backing elements secured to said tank and having radially inwardly extending bristles.

10. The structure recited in claim 9 and including at least two pairs of elongated and generally upright shaped channels disposed helically about said axis and affixed to the tank, each channel in each pair cooperating with the other channel in the corresponding pair for receiving and carrying one of said brushes therein, and said brushes each comprising a plurality of brush segments, each segment being adapted to be carried between a pair of said channels and being adapted to be stacked upon another brush segment and in alignment therewith in said channels.

11. A ball-cleaning device comprising a substantially enclosed tank for containing a quantity of liquid therein and having an open upper portion, an elongated rigid element having a handle swiveled thereon in substantial alignment therewith and said rigid element being shiftably mounted in an upright position in said tank for substantially vertical reciprocating movement through the open upper portion thereof, guide means mounted on said tank and engaging said rigid element for guiding the same in vertical movement, camming means connected with said rigid element and said tank and being constructed and arranged for rotating said element about an axis extending substantially parallel to said element as the same is vertically shifted, said rigid element having an opening therein of substantially enlarged size relative to the diameter of said ball and forming a seat for carrying the same, at least a portion of said opening being formed eccentrically of said axis for carrying said ball therein and revolving the same eccentrically about said axis when said rigid element is vertically shifted, and ball-scrubbing means mounted in said tank and protruding inwardly toward said axis for engaging said ball when the same is eccentrically rotated for cleaning and separately turning said ball about its own center.

12. The structure recited in claim 11 and including an abutment affixed to said tank and a stop member connected with said rigid element and being shiftable therewith into engagement with said abutment for restricting upward shifting of said rigid element, and thereby defining an upper limit of vertical travel of said rigid element and of said ball seat, and a retaining element mounted on said tank adjacent the upper limit of vertical travel of said ball seat and substantially encircling said rigid element for retaining said ball on said seat when said rigid element is shifted to its upper limit of travel.

13. The structure recited in claim 12 and including a closure cover affixed to said rigid element and being shiftable therewith into engagement with said retaining element to substantially close the open upper portion of said tank when said rigid element is shifted inwardly thereof.

14. A ball-cleaning device comprising an open-topped tank for containing a quantity of liquid therein, yieldable ball-scrubbing means carried within said tank and having a substantially cylindrically shaped upright opening therein communicating with the open top of the tank, a ver-

5 tically reciprocable paddle mounted in said upright opening, helically disposed camming guide means connected with said paddle and with said tank and being constructed and arranged to rotate said paddle about an axis extending centrally and longitudinally through said cylindrical opening when said paddle is vertically reciprocated, said paddle having a ball-carrying opening therein constructed and arranged to receive and carry a ball eccentrically of said rotation axis when said paddle is reciprocated, said reciprocable paddle moving said ball eccentrically about said axis in a spiralling orbital path and in engagement with said scrubbing means and thereby causing the ball to be rotated about its own center and thoroughly scrubbed by said scrubbing means, and a handle rotatably secured to said paddle for reciprocating the same.

10 15. A ball-cleaning device comprising a tank for containing a quantity of liquid therein and having an open top, yieldable ball-scrubbing means carried within said tank and having an elongated vertically disposed opening therein communicating with the open top of the tank, said opening having transverse dimensions slightly smaller than the diameter of the ball, a vertically reciprocable paddle mounted in said opening, spirally disposed guide means connected with said paddle and with said tank and being constructed and arranged to rotate said paddle when the same is vertically reciprocated and about an axis extending centrally and longitudinally through the vertical opening in said scrubbing means, said paddle having an oblong ball-carrying opening therein obliquely oriented with respect to the rotation axis of said paddle, said oblong opening having at least one ball-carrying end portion disposed eccentrically of said axis and being adapted for carrying a ball therein in a spiralling orbital path in engagement with the scrubbing means when said paddle is reciprocated and thereby cause the ball to be cleaned and rotated in multi-directions about its own center by said scrubbing means, and a handle rotatably secured to said paddle and extending outwardly of the tank for reciprocating the paddle.
